CLAIM

The ornamental design for a closure for a container, as shown and described.

DESCRIPTION

FIG. 1 is a top perspective view of a closure for a container in accordance with our new design in a closed configuration; FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

The oblique shade lines on the top of the closure in FIGS. 1 and 5 show a reflective or shiny surface and not surface ornamentation.

The broken lines depict portions of the closure that form no part of the claimed design.
